(57) **CLAIM**

The ornamental design for a micro flow channel chip, as shown and described.

DESCRIPTION

FIG. 1 is a top plan view of a micro flow channel chip showing our new design, a bottom plan view thereof being a mirror image;

FIG. 2 is a front elevational view thereof, a rear elevational view being a mirror image;

FIG. 3 is a right side elevational view thereof, a left side elevational view being a mirror image;

FIG. 4 is a partially enlarged top plan view thereof within the area designated as 4 of FIG. 1;

FIG. 5 is a partially enlarged front elevational view thereof within the area designated as 5 of FIG. 2;

FIG. 6 is a partially enlarged right side elevational view thereof within the area designated as 6 of FIG. 3;

FIG. 7 is a partially enlarged top plan view thereof within the area designated as 7 of FIG. 1; and,

FIG. 8 is a partially enlarged front elevational view thereof within the area designated as 8 of FIG. 2.

The broken lines illustrating unclaimed portions of the micro flow channel chip form no part of the claimed design.

1 Claim, 4 Drawing Sheets
